UNITED STATES PATENT OFFICE

2,338,943

INTERLOCK

Daniel K. Hughes, Dayton, Ohio, assignor to The National Cash Register Company, Dayton, Ohio, a corporation of Maryland

Original application August 25, 1938, Serial No. 226,690. Divided and this application August 20, 1941, Serial No. 407,665

4 Claims. (Cl. 101—96)

This invention relates to cash registers and more particularly to means for insuring that a printing operation which has been begun will be completed.

This application is a division of the application for Letters Patent of the United States, Serial No. 226,690, which was filed by Daniel K. Hughes on August 25, 1938, and which issued on October 6, 1942, as United States Patent No. 2,297,961.

In cash registers of the type to which the instant invention is applied, impression mechanism is shiftable from a normal or home position to a position opposite one or another of a plurality of sets of type wheels to print amounts therefrom. To insure that an impression will be made whenever the impression mechanism is shifted from home position, a set of levers are set when the impression mechanism is moved from home position and prevent the impression mechanism from being restored to home position unless the levers are reset by an impression being made.

It is an object of the invention, therefore, to provide means to compel the completion of any printing operation when it is once initiated.

A further object of the invention is to prevent the impression mechanism from being restored to home position, when it is moved therefrom to take an impression from type, until after the impression is actually made.

With these and incidental objects in view, the invention includes certain novel features of construction and combinations of parts, the essential elements of which are set forth in appended claims and a preferred form or embodiment of which is hereinafter described with reference to the drawing which accompanies and forms a part of this specification.

In the drawing:

Fig. 1 is a vertical section from front to rear through the middle portion of the printing mechanism as viewed from the left.

Fig. 2 is a detail showing the mechanism for forcing a complete operation of the printing mechanism before it may be returned to home position.

Fig. 3 is a detail showing, in moved or blocking position, the mechanism for forcing a complete operation of the printing mechanism before the printing mechanism can be returned to home position.

General description

The machine in which the instant invention is embodied is provided with three sets of printing

wheels, one of said sets of wheels being detail printing wheels which are set according to the amounts of entries and the other two sets of printing wheels forming totalizers which may 5 accumulate totals of the amounts of the entries and from which these totals may be printed.

In order that the various amounts may be printed, a rockable frame containing a platen, record material, and a ribbon is provided. This 10 frame normally occupies a position in which the platen is opposite the detail printing wheels, and during every amount entry the platen is operated to print the amount on the record material. When it is desired to print a total from either 15 of the totalizers, the frame is rocked from its home position to bring the platen, the record material, and the ribbon opposite the selected totalizer and to operate the platen to print the total on the record strip. To prevent any mis- 20 operation of the machine and to insure that a printing operation from a totalizer, once begun, will be completed, a system of levers is provided, which levers are moved to blocking position when the frame is rocked from its home position and 25 block the return of the frame until the levers are restored from blocking position by the platen-operating means during a printing operation of the platen. It is this system of levers, their setting to blocking position, and their restoration, 30 with which this invention is concerned.

Detailed description

Only those details of the detail printer, the totalizer, the actuating means therefor, and the 35 printing means which are necessary for an understanding of the instant invention will be described herein. For further details of these mechanisms, reference may be had to Patent No. 2,297,961, of which this application is a division.

40 *Frame for supporting the detail printer and the totalizers*

Mounted on a cross member 51 and a shaft 77 are a right printing wheel support frame plate 78 (Fig. 1) and a left frame plate (not shown), 45 which are spaced by appropriate rods and shafts. The side plates are secured to flanges (not shown) projecting from a rear plate 303.

Detail printer

The detail printer includes a plurality of type wheels D (Fig. 1), which are settable according to entered amounts and which are rotatably carried by a shaft 83 supported by the printing wheel 50 support frame plates.

Totalizers

Two totalizers are provided in the instant machine. Each totalizer includes a plurality of type wheels which can be operated selectively to accumulate amounts and from which totals may be printed. The wheels of the "I" totalizer are rotatably supported on a shaft 85 (Fig. 1), and those of the "II" totalizer are rotatably supported on a shaft 86. The totalizer-supporting shafts 85 and 86 are carried by rockable frames (not shown) mounted in the printing wheel support frame plates before mentioned.

Printing mechanism

Rockably mounted on cross member 51 (Fig. 1) by claws 105 is the printer frame consisting of a right frame plate 100 and a left frame plate (not shown) spaced apart and secured by rods 102, 103, and 104 so as to form a supporting frame for the printing mechanism.

In normal position, the center of gravity of the printer frame and the mechanism which it supports is to the rear of and above cross member 51, causing the frame to stay rocked rearwardly, where it is supported on a portion of the rear frame plate 303 (Fig. 1) serving this purpose.

In printing transaction data from the detail printing wheels onto the record strip, the printer frame is not moved from its normal position, as the platen is then directly over the printing line of said wheels.

When printing transactions from either the "I" or the "II" totalizer printing wheels, the printer frame is rocked forward to one of two positions, determined by stops, so as to position the platen 115 to take an impression from the "I" totalizer wheels or the "II" totalizer wheels, as selected by manipulative means to be hereinafter described.

On the left side of the right frame plate 100 of the printer frame (Fig. 1) is a stud 161, on which is pivotally mounted a printing hammer 162 having a normal position in which it rests on the upper edge of the horizontal arm of a bell crank lever 163, which is also pivotally mounted on stud 161. Bell crank lever 163 and the printing hammer not being in the same plane, the forward or striking portion of the hammer has welded to it an extra width of metal to bring it into the plane of bell-crank 163, upon which it rests, said extra width of metal serving the additional purpose of weighting the hammer. Bell crank lever 163 is urged normally counter-clockwise by springs 164 and 165 against a portion of frame 100, an offset bearing edge 166 being provided on the downwardly-extending arm of bell crank 163 for that purpose. Bell crank 163 thus may be moved clockwise only, against the force of springs 164 and 165. This movement of bell crank lever 163 occurs each machine operation through a cam 167 secured on a drive shaft 36, which engages a roller stud 168 on the bell crank lever 163, forcing it clockwise. At approximately the middle of the operating cycle, the cam 167 presents an abrupt break allowing the springs 164 and 165 to pull the bell crank lever 163 sharply counter-clockwise to its stopping point. Hammer 162 is likewise carried counter-clockwise, but continues moving under its own momentum after bell crank lever 163 has been stopped.

Inasmuch as means for rotating the drive shaft 36 forms no part of the instant invention, this means will not be described in detail herein. Reference may be had to the above-men-

tioned United States Patent No. 2,297,961 for these details.

Platen 115 (Fig. 1) is mounted in a frame 169 pivotally mounted on rod 114 journaled in the printer frames. Clutched by a tongue-and-groove connection to the frame 169 is a rearwardly-extending arm 170, the under side of the rear end of which arm is adapted to be struck by the hammer 162, causing the platen to carry a record strip against the printing wheels. The forward end of arm 170 has a thumb piece by which the arm may be moved on rod 114 to the right, unclutching the arm from the frame 169. The thumb piece is normally held to the left, in which position frame 169 and arm 170 move as a unit.

Attached on the inside of printer frame 100 is a shield 190 (Fig. 1) preventing the operator from holding the rear end of arm 170 so it will be unaffected by the hammer blow.

Spring 171 normally holds the platen slightly away from the printing wheels by holding the rear end of arm 170 against stud 172. A bent-over portion 173 of lever 137 locks the platen against printing movement unless lever 137 has been rocked in a printing operation.

The printer frame also carries record material supporting and feeding mechanism and a ribbon supply mechanism. These mechanisms will not be described herein, as they are not essential to an understanding of the instant invention. Reference may be had to the above-mentioned United States Patent No. 2,297,961 for details of these mechanisms if such details are desired.

As shown in Fig. 1, the record material 106, in its movement from a supply roll (not shown) to a storage roll (not shown), passes over the rods 103 and 114, thence around the platen 115, and back over the rods 114 and 103.

The platen 115 (Fig. 1) is normally over the detail printer wheels on shaft 83 so as to be in proper position on each machine operation to print the amount involved in the transaction.

On total-taking operations, the platen and the record material must be moved so as to be over the "I" or the "II" totalizer. This is accomplished by rocking the printer frame forward around cross member 51 until the platen is over the selected totalizer.

As the cam 167 rotates only during a machine operation in which an impression is taken from the detail printer, other means is provided for actuating the hammer in total-printing operations which involve no rotation of shaft 36.

If the operator wishes to print from the "I" totalizer, lever 137 (Fig. 1) is grasped by the handle 178 and drawn forward and downward, which rocks the printer frame and associated parts around cross member 51. When lever 137 is manually rocked clockwise, shoulder 174 engages pawl 175 pivotally mounted on hammer 162 by stud 176 and normally held clockwise by a spring against an adjustable screw stop 177, causing further clockwise rocking of lever 137 to rock hammer 162 clockwise against the action of springs 164 and 165. Due to the distance between centers 136 and 161, the shoulder 174 will eventually slide over pawl 175, allowing the springs 164 and 165 to cause the hammer to strike the platen a blow. On the return counterclockwise rocking of lever 137, shoulder 174 by-passes pawl 175, causing it to rock counter-clockwise as viewed in Fig. 1. During the operation of the lever 137, a stud 179

extending from lever 137 enters cam slot 180 in the right printing wheel support plate 78, which slot is so shaped that lever 137 is rocked slightly clockwise with relation to the printer frame and cocks the hammer. The hammer is released as stud 179 reaches the bottom of the slot. The stud engaging the bottom of the slot 180 also positions the printer frame so that the platen will be over the "I" counter.

If the operator wishes to print from the "II" counter, the printer frame is drawn forward by the handle 188, which causes stud 179 to enter cam slot 189 in the right printing wheel support plate 78 and allows the printer to rock forward until the platen is over the "II" counter. This cam slot is also formed so as to cock the hammer and release it as stud 179 reaches the bottom of the slot. In drawing the printer forward by handle 178, lever 137 moves slightly before the printer starts, thus causing stud 179 to enter slot 180 instead of slot 189, which it enters when handle 188 is used.

As lever 137 is drawn forward by handle 178, a bracket 191 (Fig. 2) attached thereto is interposed between arm 170 and frame plate 100, preventing the shifting of arm 170 to the right to disable the platen.

Device preventing incomplete total-printing operation

One of the novel features of the invention is a device which prevents the printer frame from being returned to home position, after being therefrom, unless a complete total-taking operation is performed, thus requiring an impression to be taken from the selected totalizer. This device prevents the operator from manipulating the printer in such a manner that a totalizer might be reset without an impression of the amount standing thereon being first taken.

Mounted on the left of printer frame 100 (Figs. 1, 2, and 3) are two levers 159 and 158, which are pivoted on studs 161 and 160. These levers are normally in the position shown in Fig. 2 when the printer frame is in home position, with the lever 159 resting against the rear frame plate 303. When the printer frame is rocked forward, spring 157 (Fig. 2) tends to rotate the levers 159 and 158 each clockwise as seen in Fig. 2, the lever 159 rotating to the position shown in Fig. 3, and the lever 158 rotating so that the rear part of lever 158 engages notch 156 in the periphery of lever 159, to latch lever 159 in moved position and prevent the printer frame from being returned to home position, as the rear end of lever 159 will then strike the rear frame plate 303 before the printer frame reaches home position. During the rocking of the printer frame forward, the stud 179 (Fig. 1), as explained, will enter either cam slot 180 or 189, rocking lever 137 clockwise in relation to the printer frame as viewed in Fig. 1. As the rocking of lever 137 occurs before the lever 159 has moved to bring notch 156 opposite the rear part of the lever 158, the stud 91 on lever 137 will be out of the path of lever 158 as the lever turns clockwise on stud 160 to enter into latching engagement with the notch 156. The notch 90 in lever 158 accommodates stud 91 during the remainder of the forward operation of the lever 137. Levers 158 and 159 remain engaged until the lever 137 has actuated the printing hammer and until the return movement of lever 137, which, in bypassing bell crank lever

175, rocks the bell crank lever 175 counter-clockwise, as viewed in Fig. 3, to the position shown in dot-and-dash outline in this figure, so that the upper extending arm of the bell crank 5 175 strikes the forward extending part 155 of lever 158 and rocks this lever clockwise, as viewed in Fig. 3, to the position shown in dot-and-dash outline, in which position lever 158 is out of latching engagement with notch 156, 10 and out of the path of stud 91 as lever 137 moves home. When lever 137 returns to home position, stud 91 is positioned over lever 158 and prevents this lever from engaging notch 156. When the lever 158 is moved out of latching 15 relation with notch 156, lever 159 can be rotated clockwise as viewed in Fig. 1 and counter-clockwise as viewed in Fig. 2 by the movement of the printer frame, which is now allowed to return to home position.

Automatic hammer adjustment

In the instant machine, printing from the detail printing wheels involves only five characters, printing from either totalizer involves seven characters, and provision has been made for causing the hammer to strike a more forceful blow when printing a total from the "I" or the "II" totalizer than it does when printing the transactions from the detail printing wheels on registering operations. This mechanism will now be described.

30 Springs 164 and 165 are attached at their rear ends to the bell crank lever 163. The front end of spring 165 is attached to stud 181 on the right printer frame 100. The front end of spring 164 is attached to stud 182 on a lever 183 pivoted on stud 184 extending from the right frame 100 of the printer. Secured to the right side of the right printing wheel support frame 78 is a cam 185 which guides a roller 186 mounted on a downwardly-extending arm of lever 183. As the printer frame is rocked forward for total taking, the roller 186 travels along cam 185, stretching spring 164. On total-printing operations involving either the "I" or the "II" totalizer, the roller reaches the surface 187, which is arcuate, having cross member 51 as a center, thus causing the hammer blows on the "I" and on the "II" totalizers to be of the same force.

It is believed that the operation of various 50 mechanisms described above, and particularly the interlock for preventing the return of the printing frame to home or normal position until after a printing impression has been made, is clear from the above description, and no further description of the operation of these mechanisms is necessary.

While the form of mechanism herein shown and described is admirably adapted to fulfill the objects primarily stated, it is to be understood that 60 it is not intended to confine the invention to the one form or embodiment herein disclosed, for it is susceptible of embodiment in various forms all coming within the scope of the claims which follow.

What is claimed is:

1. In a machine of the class described, the combination of a printer platen shifttable from a normal home position to another position in which an impression is to be made; means to 70 actuate the platen to cause an impression to be made when the platen is in said other position; a pair of levers shifttable with the platen as the platen moves from home position; means for moving one of said levers to blocking position as it is shifted with the platen and for moving the

other of said levers to latch said one lever in blocking position to prevent the return of the platen to normal home position; and means on said other lever engageable by said actuating means, after the platen has been actuated, to unlatch said one lever to allow it to be moved from blocking position when the platen is shifted to its normal home position.

2. In a machine of the class described, the combination of a plurality of sets of type wheels; a platen; a frame supporting said platen, said frame being rockable from a home position to bring the platen selectively opposite various ones of said sets of printing wheels; means carried by the frame and movable from a normal position to actuate the platen after the platen has been positioned opposite a set of type wheels; a plurality of cooperating levers carried by the frame, one of said levers being movable to blocking position to prevent the return movement of the frame to home position and the other of said levers being movable to latch said one lever in blocking position; means to move said one lever to blocking position as the frame moves from home position and to move said other lever to latching position; means on the actuating means for preventing the latching movement of said other lever until the actuating means has moved out of home position to actuate the platen; and means on said other lever engageable by the actuating means, as it returns to home position after actuating the platen, for shifting said other lever out of latching position to allow the one lever to be moved out of blocking position and enable the frame to be returned to home position.

3. In a machine of the class described, the combination of a plurality of sets of type wheels; a platen; a frame supporting said platen, said frame being rockable from a home position to bring the platen selectively opposite various ones of said sets of wheels; platen operating means; a printing hammer for operating said platen to take impressions from said type wheels and a lever, carried by said frame, rockable relative thereto, and operable, as the frame is moved from home position to bring the platen opposite any selected one of said sets of wheels, for causing the operation of said hammer means; a blocking lever carried by said frame and normally out of blocking position; means for moving the blocking lever to blocking position as the frame is moved from home position; a retaining lever engageable with said blocking lever to retain the blocking lever in blocking position to prevent the return movement of the frame to home position; means on said first-mentioned lever for holding the retain-

ing lever out of retaining engagement with the blocking lever until the first-mentioned lever has rocked relative to the frame; and means on the retaining lever by which the retaining lever can be moved by the platen operating means to release the blocking lever as the first-mentioned lever is returned after causing the operation of the hammer, the operation of the blocking lever being such that it will prevent the return of the printing frame to home position until after the platen has been operated.

4. In a machine of the class described, the combination of a machine frame member; a plurality of sets of type wheels; a platen; a printer frame for supporting said platen, said printer frame being normally in home position where a portion thereof engages the machine frame, but rockable from said home position to bring the platen opposite selected ones of said sets of type wheels; platen operating means including a hammer for actuating the platen to take impressions from the selected sets of type wheels, and a lever, carried by said frame, rockable relative thereto, and operable, as the frame is moved from home position to bring the platen opposite the selected set of type wheels, to cause an operation of the hammer; a blocking lever pivotally carried by the printer frame at a point adjacent where it engages the machine frame, said blocking lever having a notch therein and being normally within the printer frame and out of blocking position; means to move the blocking lever from within the printer frame as the printer frame moves from its home position, said blocking lever moving to a position where it will engage the machine frame member and block the return of the printer frame to home position; a retaining lever pivotally carried by the printer frame and having a shoulder movable into engagement with the notch in the blocking pawl to retain the blocking pawl in blocking position; means on said first-mentioned lever cooperating with the retaining lever to prevent the engagement of the shoulder with the notch on the blocking lever until the first-mentioned lever is moved when the printer frame moves from home position; and means on the retaining lever by which the retaining lever can be moved by the platen operating means to remove the shoulder from the notch on the blocking lever as said first-mentioned lever is returned with the printer frame to home position, whereby to allow said blocking lever to be moved within said printer frame and enable the printer frame to be returned to home position.

CERTIFICATE OF CORRECTION.

Patent No. 2,338,943.

January 11, 1944.

DANIEL K. HUGHES.

It is hereby certified that error appears in the printed specification of the above numbered patent requiring correction as follows: Page 4, first column, line 41, claim 3, after "means" strike out the semi-colon and insert instead --including--; and that the said Letters Patent should be read with this correction therein that the same may conform to the record of the case in the Patent Office.

Signed and sealed this 14th day of March, A. D. 1944.

Leslie Frazer

Acting Commissioner of Patents.
